UNITED STATES PATENT OFFICE.

WILLIAM H. MINNIX, OF WASHINGTON, DISTRICT OF COLUMBIA.

ADJUSTABLE AND PORTABLE FLOWER-STAND.

SPECIFICATION forming part of Letters Patent No. 635,940, dated October 31, 1899.

Application filed August 10, 1899. Serial No. 726,766. (No model.)

To all whom it may concern:

Be it known that I, WILLIAM H. MINNIX, a citizen of the United States, residing at Washington, District of Columbia, have invented 5 certain new and useful Improvements in Adjustable and Portable Flower-Stands; and I do hereby declare the following to be a full, clear, and exact description of the invention, such as will enable others skilled in the art to 10 which it appertains to make and use the same.

This invention relates to a new and useful improvement in folding stands for plants, flowers, &c.

The invention consists in the construction 15 hereinafter set forth.

In the annexed drawings, Figure 1 represents the frame of the stand with parts ready 20 to be put into place. Fig. 2 represents the device complete. Fig. 3 is a top view showing the method of securing the supports together. Figs. 4, 5, and 6 are details of construction.

In the drawings the letters A A' A² indicate the supports, which are alike, being 25 substantially triangular. They consist of the uprights a, the inclines a', and the cross-braces a² at the bottom. The inclines a' and cross-braces a² are preferably connected by 30 hinges a³ to the uprights a. Projecting at stated intervals from the inclines a' are rests B. These rests have forks b, which straddle the inclines, and bolts passing through them 35 secure them together. The several supports are preferably held together by the hinges a⁴. Near the top each upright a has a hole or slot c, and through these several holes passes a curved stay or brace C. Secured to the tops 40 of the supports A' and A² are two curved quadrant-shaped tracks D' and D². These tracks are concaved on top, and one, D', is narrower than the other, D², so that they may slide past

each other. A cover E is fastened to the top of the support A and has on its under side a track e, concaved underneath and fitting the two tracks D' D². Between the upper and 45 lower tracks are placed several antifriction-balls d. There may be supplemental supports A³, each being simply an incline a, having the rests B and with a hook a⁵ at the top to catch over the stay or brace C. Upon the 50 rests B are held the shelves F. These consist of sections f, substantially alike in shape and size, having the rims f', which when in place form continuous shelves about the stand. These shelf-sections are held in place 55 by fastenings f², which pass down through the sections into the rests. Where two sections come together, a pronged fastening may be used.

It will be seen that the construction de-60 scribed forms a folding stand. The shelf-sections may be removed after withdrawing their fastenings. The supplemental supports A³ are unhooked and the supports A swung upon the hinges a⁴. The brace or stay C slides 65 through the holes c, and the supports come flat together. To put up the stand, the action is reversed.

Having described my invention, what I 70 claim is—

A folding stand for plants, consisting of the several supports hinged together, the stay or brace passing through the tops of the supports; the supplemental supports having hooked ends, all the supports having rests, 75 and the shelf-sections as set forth.

In testimony whereof I affix my signature in presence or two witnesses.

WILLIAM H. MINNIX.
